SYRINGE

Filed Feb. 9, 1928

*Inventor
Willard H. Brockway*

*Elvis Spear Jr.
By Attorney*

UNITED STATES PATENT OFFICE

WILLARD H. BROCKWAY, OF NEEDHAM, MASSACHUSETTS, ASSIGNOR TO MACGREGOR INSTRUMENT COMPANY, OF NEEDHAM, MASSACHUSETTS, A CORPORATION OF MASSACHUSETTS

SYRINGE

Application filed February 9, 1928. Serial No. 252,984.

In certain types of syringes, notably those for surgical and dental use, the provision for a frictional control of the plunger is a factor greatly desired. As my present invention has 5 been developed particularly with such types of syringe in view, I shall discuss it in connection therewith as it affords a convenient illustration of the principles involved and is a form that I have found well adapted to 10 use and convenient and inexpensive to manufacture.

In such a syringe the friction on the plunger is of great importance because these 15 syringes are frequently operated from an inverted position. In the case of an open end syringe in which the plunger is removable, there is danger of having the plunger fall out if it is not restrained; or even if the plunger is withheld from actual dropping 20 out, it is awkward for the surgeon if the plunger moves at all, both because of loss of contact with the fluid contents and because the position of the thumb piece is changed and not easily re-engaged without shifting 25 the position of the hand.

For the purposes of illustration I have shown in the accompanying drawings a form 30 of syringe embodying my invention. To these drawings I have made reference by characters applied throughout the specification.

In the drawings:—

Fig. 1 is a general view of my syringe.

Fig. 2 is an enlarged fragmentary section 35 of a preferred form thereof showing the device in frictioning position.

Fig. 3, a similar view of a modified form of my invention in non-frictioning position showing the raising of the plunger, and

Fig. 4, a section on the line 4—4 of Fig. 3. 40 I have indicated at 1 the barrel which in this form of syringe is a glass tube into which is closely fitted a plunger 2. The barrel 1 has the usual fittings and needle attachment at its lower end, but these need not be considered as they are not involved in my present 45 invention.

In a preferred form of embodiment of my invention I provide on the upper end of the barrel 1 a threaded collar 3 cemented to the 50 glass barrel. This collar is screwed into a

cap 4 which carries the finger rings 5. The cap 4 is provided with a shoulder 6. This may be a bushing pressed into and becoming a part of the cap 4 or may be produced as a part of the cap casting. This shoulder 6 forms a bearing for the plunger 2 and in this form of my device has an inclined bearing surface on its inner face. 55

Between the shoulder 6 and the top of the barrel 1 is left a space which constitutes 60 an annular channel 7 in the body or barrel of the syringe when considered as a whole. It will be understood that this channel 7 may be variously formed but in the construction shown is very cheaply and conveniently 65 made by this spacing of the glass barrel 1 from the shoulder 6.

Located within this space 7 is a friction piece 8. This piece 8 is in the form shown 70 a split ring or annulus the faces of which are parallel and each edge of which is in a plane perpendicular to its bore which receives the plunger with a close but free fit. The ring 8 therefore with its slight clearance on the plunger 2, when the ring 8 is 75 aligned with the axis of the plunger, permits the free movement of the plunger through the ring. This is true generally on the delivering stroke of the plunger as well as on the upward or charging stroke. For the reasons 80 stated above, however, it is not desirable that the plunger be free from the barrel in all positions notably in inverted positions. 85

Still referring to the form of my invention shown in Fig. 2 on the inward or delivery stroke of the piston 2, the friction ring 8 finds bearing on the top of the barrel and its axis is perpendicular to the axis of the piston. When, however, the syringe is tipped or inverted or there is any sudden pull on the 90 plunger 2 the friction ring 8 tilts and assumes the frictioning position indicated in Fig. 2 and rests against the inclined shoulder 6 so that its axis is at an angle to the axis of the plunger and its periphery is brought into 95 contact with the plunger 2. This provides a frictional engagement of the edges of the ring 8 with the plunger walls so that considerable force is needed to withdraw the plunger 2. Any likelihood of the plunger 2 100

slipping or dropping from the barrel is entirely obviated.

In the modifications shown in Fig. 3 instead of providing an inclined or angular surface on the inside of the cap 4, as, for example, the shoulder 6, I provide a friction ring such as that indicated at 8'. This friction ring 8' has an annular or inclined plane on one edge and is shown in non-frictional position in Fig. 3. In operation, the ring is placed in the recess 7 with its inclined face outward. If the syringe is inverted this inclined face finds bearing against the horizontal wall 4' of the cap 4 placing the ring in frictioning position similar to that illustrated in Fig. 2. This same position is assumed by the ring 8 on a sudden withdrawal stroke of the plunger 2, the axis of the ring then being at an angle to the axis of the plunger and its periphery engaging the plunger. It will be understood that either embodiment of my invention provides a highly satisfactory operating condition. The plunger is entirely free to move inwardly or outwardly offering no resistance at all to the thumb pressure of the operator, but any upsetting or accidental deviation will cause the ring to assume frictioning position and hold the plunger locked until deliberately adjusted by the user.

In the foregoing I have discussed my lock in its purely automatic function. There is, however, another important phase of my invention which relates to the control of the plunger lock so that it can be rendered inoperative when desired. It is a combinative feature of great importance but one that may be omitted in types of syringes where control of the lock is not necessary.

In certain work, notably in local anesthesia, it is desired to operate a syringe intermittently during perhaps a very extended operation and with the patient in a great variety of postures. It is therefore important that the syringe lock itself when not in operation, and yet be readily operated by the user regardless of the posture of the patient.

To this end my invention contemplates the provision of a positive control as illustrated in Fig. 2. In this figure I have shown the cap as apertured at 9 for the reception of a plunger 10 controlled by a spring 11. This spring 11 fits within a channel or groove in the finger ring 5 for a part of its circumference and then departs from its inner surface with a sufficient clearance so that when the operator's finger is within the ring the plunger 10 is projecting into the cavity 7 behind the ring 8 or 8' as the structure might be. This prevents the ring from tilting and insures a free movement of the plunger during operation. As soon as the operator's finger is withdrawn from the ring the plunger 10 is removed from its position behind the

locking piece and it may tilt to lock the plunger in place.

Various modifications may obviously be made in the construction of the syringe and the form shown will obviously be modified in case of different types and different classes of syringe. My invention is furthermore capable of application to moving parts in other than syringes. All such modifications, variants and adaptations are to be construed as within the purview of my invention if consistent with the appended claims.

What I therefore claim and desire to secure by Letters Patent is:

1. In a syringe, a barrel, a plunger, and a plunger lock comprising a relatively flat plunger locking member having a free fit on the plunger, and a rear stop for the locking member, said member and stop having a plane of contact out of the perpendicular of the plunger axis.

2. In a syringe, a recessed barrel, a plunger moving in said barrel, a plunger lock in said recess and means for rendering said lock ineffective comprising a spring controlled member adapted to be projected into said recess behind said lock.

3. In a syringe, a recessed barrel and a plunger moving in said barrel, the walls of said barrel providing a plunger bearing, said recessed portion having a face inclined to the plunger axis, a friction ring disposed in said recess adapted to rest on said inclined face when said syringe is tilted from the vertical whereby its edges frictionally engage said plunger, and means for rendering said lock ineffective comprising a spring controlled member, adapted to be projected into said recess behind said ring to prevent the same from frictionally locking said plunger against free movement during operation.

4. In a syringe, a barrel and a plunger, a bored cap on said barrel provided with a grooved finger ring, an apertured annular channel in said barrel, a plunger engaging frictional member in said channel and means for rendering said frictional member ineffective comprising a spring controlled member located in said aperture in said barrel, said spring fitting within said groove in said finger ring for a part of its circumference and then departing from its inner surface with a sufficient clearance whereby when the operator's finger is within the ring said spring controlled member is projected through said aperture into said channel behind said frictional ring thus preventing engagement thereon with said plunger.

5. In a syringe, a barrel, a plunger, a plunger locking ring having a free fit on the plunger and a rear stop for the locking ring, said ring and stop having a plane of contact out of the perpendicular of the plunger axis.

6. In a syringe, a barrel, a plunger disposed therethrough, a recessed rear stop for

the plunger, and a locking member in said recess having a free fit on the plunger, said plunger stop and locking member having an inclined plane of contact out of the perpendicular of the plunger axis when said syringe is in other than downwardly inclined position.

7. In a syringe, a barrel, a plunger and a tiltable gravity plunger locking ring having a free fit on the plunger when the syringe is in downwardly inclined position, and a friction fit when the syringe is upwardly inclined.

8. In a syringe, a barrel, a plunger and a tiltable gravity plunger locking ring having a free fit on the plunger in one position and a friction fit in its other position.

9. In a syringe, a barrel, a plunger and a gravity plunger lock having a plunger receiving bore normally coaxial with the plunger but angularly disposed thereto when the lock is tilted upon the inversion of the syringe.

10. In a syringe, a barrel, and a plunger, said barrel having a plunger encircling recess, a gravity plunger lock having a free fit on the plunger and tiltably positioned in said recess, said lock and recess having contacting surfaces in one position of tilt of the lock.

11. In combination an hypodermic syringe having a needle and a fluid expelling means, and means comprising a single member located adjacent the latter to permit movement toward the needle and to grip and frictionally bind the fluid expelling means against movement away from said needle, thereby to prevent suctional action through the needle.

In testimony whereof I affix my signature.
